UNITED STATES PATENT OFFICE.

JAMES THORNE AND EBENEZER BANTON BURR, OF LONDON, ENGLAND;
SAID BURR ASSIGNOR TO SAID THORNE.

ELECTRICAL HEAD-LIGHT.

SPECIFICATION forming part of Letters Patent No. 436,677, dated September 16, 1890.

Application filed July 2, 1888. Serial No. 278,744. (No model.) Patented in England February 12, 1887, No. 2,262, and May 13, 1887, No. 7,046; in Belgium April 30, 1888, No. 81,377, and in France June 8, 1888, No. 189,824.

To all whom it may concern:

Be it known that we, JAMES THORNE, merchant, and EBENEZER BANTON BURR, engineer, subjects of the Queen of Great Britain, and both residents of London, England, have invented new and useful Improvements in Signal and other Lamps, (for which we have obtained patents in Great Britain, No. 2,262, dated February 12, 1887, and No. 7,046, dated May 13, 1887; in France, No. 189,824, dated June 8, 1888, and in Belgium, No. 81,377, dated April 30, 1888,) of which the following is a specification, reference being had to the accompanying drawings.

15 The main object of the present invention is to provide an electric "head-lamp," "tail-lamp," "side-lamp," or other signal-lamp for railway purposes, which will be complete in itself, having no external wires or connections.

20 The present improvements are, however, applicable to mast-head lamps or other signal-lamps for ships, to lamps for omnibuses, tramway-cars, cabs, velocipedes, or other vehicles, and also to lamps for telegraphing by means 25 of "flashing-signals" and for mining or other purposes.

In our improved lamp we employ a lens, of which the interior surface is plane and the exterior surface is so curved in one sweep as to 30 give a parallel or nearly parallel beam from a point. The curvature of the exterior surface of the lens should for this purpose be parabolic or approximately parabolic, or elliptic or approximately elliptic. We sometimes employ a reflector of corresponding form and so 35 arrange the said lens and reflector relatively to each other and to the light that their foci correspond with each other or lie in the axial line common to both lens and reflector, and 40 the rays of light concentrated by the reflector will pass through the lens. By reason of the peculiar formation and arrangement of the lens and reflector we are enabled to place the light and reflector nearer the lens than heretofore, and thus economize space in the lamp. 45 Moreover, in a lamp provided with our improved lens and reflector, instead of the shape of the light or flame of the lamp being visible through the lens, as in lamps heretofore con-

structed, the lens presents the appearance of 50 an illuminated disk, the light having substantially the same brilliancy over the entire area of the lens, and the lamp throws out a beam of intense light, which can be seen at a great distance from the lamp. We thus obtain much 55 better results than heretofore with respect to the intensity of the beam projected from the lamp.

We combine with a lantern or lamp-casing in the manner herein described an electric incandescent lamp, an electric battery or accumulator, and a lens of the kind herein mentioned, with or without a reflector, all arranged in the said lantern or casing, so that the apparatus can be readily inserted in or 60 removed from its place on a vehicle or other object without the necessity for connecting or disconnecting any wires. Moreover, as there is no need for ventilation, the said lantern or lamp-casing can be made without a chimney 65 or ventilator and can be closed (hermetically, if desired) so as to exclude dust. We arrange the said reflector and lens relatively to each other in the manner above described—that is to say, so that their foci correspond 70 with each other, being situated in the axial line common to both lens and reflector. By this arrangement of the lens and reflector we are enabled to place the light and the reflector much nearer the lens than heretofore, and 75 thus leave space within the lantern or casing for the electric battery without the necessity for increasing the size of the lantern or casing as compared with those ordinarily used for similar purposes. Moreover, we obtain very 80 good results in respect of the intensity of the light passed through the lens.

In the accompanying drawings, Figure 1 is a vertical longitudinal central section of one form of our improved apparatus. Fig. 2 is a 85 transverse section on the line $x-x$, Fig. 1. Fig. 3 is a vertical transverse central section of another form or modification of our said apparatus; and Fig. 4 is a vertical longitudinal section on the line $x'-x'$, Fig. 3.

Like letters indicate corresponding parts throughout the drawings.

a is the lantern or lamp-casing.

b is the lens, which is secured therein in any well-known or suitable manner.

c is a parabolic reflector, which is made with a socket *c'*, adapted to fit upon a bracket *d'*, formed on or attached to a sliding plate *d*.

e is the battery, which is placed upon and, if necessary, attached to the said sliding plate.

f is an electric incandescent lamp of any suitable description, which is suspended from wires passed through a block or piece of insulating material inserted in a tube or socket *c''*, fixed in the reflector *c*, the said block or piece being secured by means of a set-screw *c''*. The plate *d* is fitted between guides *a'*, formed on or attached to the casing *a*, so that the said plate, with the battery, the lamp, and the reflector, can be very readily inserted in and removed from the said casing.

20 To provide for tightly closing the battery and at the same time firmly securing it in the casing and preventing its withdrawal except by an authorized person, we employ a screw *g*, which is passed through a tapped hole in

25 a socket *g'*, secured to the casing *a*. The lower end of this screw bears against the lid *e'* of the battery and holds the same down, so that the battery is kept tightly closed, a sheet or washer of india-rubber or other elastic material being preferably placed between the lid and body of the said battery to insure tightness of the joint. The upper end of the screw *g* is made square or of other suitable shape, so that a key may be fitted thereon to permit 30 the turning of the said screw in either direction. The said key is so made that it will fit into the hole or cavity *g''* in the socket *g*, which hole or cavity may be of any desired shape.

40 When a primary battery is employed, we prefer to use that described in the specification of former Letters Patent of Great Britain, dated September 2, A. D. 1882, No. 4,198. We may, however, use any other suitable primary battery, or we may use a secondary battery or accumulator.

45 *h* is a switch for completing or interrupting the electric circuit for the purpose of putting the apparatus into or out of action when desired.

We sometimes arrange in combination with this switch a clock-work device for indicating the length of time during which the lamp has been alight, so that the state of the 55 battery may be readily ascertained at any time. This device is so connected with the switch that when the light is turned off the movement of the clock-work will be arrested; or we use an indicator which may be adjusted 60 by hand for the purpose above specified.

Instead of making the lens of the ordinary spherical form, we prefer to make it in the form of a paraboloid—for example, as shown in the drawings. We sometimes, however, 65 make it elliptic or approximately elliptic.

Whatever may be the shape of the reflector and lens used, it is advantageous to so adjust

the reflector relatively to the lens that their foci will correspond or lie in a common axial line, as above described.

70 In some instances we dispense with the reflector shown in Figs. 1 and 2 and provide a tube, which is inserted and secured in the aperture in the front of the lantern or lamp-casing, and in the outer end of which a parabolic lens is fixed. This tube is sometimes made to serve as a reflector, in which case we prefer to make it in the form of a truncated cone or of a truncated paraboloid.

The lamp or apparatus shown in Figs. 1 and 2 will serve very efficiently as a head-lamp or tail-lamp for use on a railway-carriage or locomotive.

80 The lamp shown in Figs. 3 and 4 is designed as a side-lamp for a railway-carriage. It has two parabolic lenses *b* and a double reflector—that is to say, two parabolic reflectors *c*, portions of which are cut off through a plane perpendicular to their axes and which are united at *c''*—the electric incandescent lamp *f* being 85 placed in the center, as shown.

90 When used for railway purposes, our improved lamp affords, among others, the following advantages, viz: There are no external wires or connections. Therefore the lamp can 95 be readily transferred from one vehicle to another, and no disconnection of wires is necessary when slipping a carriage. There is no need of ventilation. Therefore the casing can be made without a chimney or ventilator, and can be tightly closed so as to exclude dust. No trimming is required, as in oil-lamps, and there is no smoke, grease, or soot to dim the lens and obscure the light. The light cannot be effected or extinguished, as in oil-lamps, by 100 air currents or eddies produced by the motion of the train or otherwise. There is no risk of fire in case of breakage of the lamp in a collision or other accident. The lamp can be easily handled, and the battery can be very 105 readily withdrawn, recharged, and replaced.

We sometimes provide interchangeable slides of green or other colored glass—as shown, for example, at *i* in Fig. 1—which can be very 110 readily inserted in and withdrawn from the lantern or lamp-casing for the purpose of changing or determining the color of the light.

115 For railway purposes our lamp has the further advantage that these slides can be changed without liability to extinction of the light when the door of the casing is opened. The necessity for any mechanical devices for changing them without opening the said casing is thus obviated.

We do not confine ourselves, save in respect 120 of lens and reflector, to any special form or construction of the parts of our improved lamp, as these will depend to a great extent upon the purpose for which the lamp is required, and can be considerably modified without departing from the nature of our said invention.

125 It is evident that our improved apparatus may be adapted for telegraphing by means of

flashing-signals by providing it with a movable shutter or disk for obscuring the light when necessary.

We do not herein claim the construction of 5 a parabolic lens, *per se*, as such forms the subject-matter of a separate application filed by us January 26, 1889, Serial No. 297,642.

What we claim is—

1. The herein-described lamp, consisting of 10 a closed casing, a lens set in said casing and having a plane interior surface and an approximately-parabolic external surface, a reflector having a contour corresponding to the exterior of the lens, the foci of said lens and reflector being in the same axial line, and an 15 electric lamp, a battery, and connections, all inclosed in the casing, substantially as shown and described.

2. The herein-described lamp or lantern, consisting of the closed casing *a*, the lens *b*, 20 having a plane interior surface and an approximately-parabolic external surface, the parabolic reflector *c*, having its focus in the same axial line with the focus of the lens, the battery *e*, incandescent lamp *f*, and battery- 25 connections, all inclosed in the casing *a*, and the switch *h* on the outside of said casing, substantially as shown and described.

In testimony whereof we have hereunto set our hands and affixed our seals this 18th day 30 of June, 1888.
